UNITED STATES PATENT OFFICE.

FELIX W. LEINBACH, OF BETHLEHEM, PENNSYLVANIA.

PAPER BAG.

SPECIFICATION forming part of Letters Patent No. 390,607, dated October 2, 1888.

Application filed March 12, 1886. Serial No. 194,962. (No model.)

To all whom it may concern:

Be it known that I, FELIX W. LEINBACH, of Bethlehem, Pennsylvania, have invented an Improvement in Paper Bags, of which the following description and claim constitute the specification, and which is illustrated by the accompanying sheet of drawings.

This invention relates to an improvement in the manner of cutting apart the edges of a tucked paper tube to form a paper bag having longitudinal inward bellows folds and a square bottom.

Figure 1 is a view of a length of tucked paper tube, and Fig. 2 is a cross section of the same. Fig. 3 is a view of the tube of Figs. 1 and 2 after its lower corners have been cut away on the diagonal broken lines of Fig.

1. Fig. 4 is a view of the tube of Fig. 3 after its lower end has been opened out and folded down so as to present the flaps shown therein. Fig. 5 is a view of the blank of Fig. 4, with its two side flaps folded back into place and with paste applied to the presented surfaces of the other two flaps. Fig. 6 is a view of the blank of Fig. 5, with one of the latter flaps folded and pasted down in place; and Fig. 7 is a view of the same with both those flaps thus folded and thus pasted and the bag thus completed. Fig. 8 is a perspective view of the bag of Fig. 7, opened out for use, but with its bottom turned upward in order to show the construction thereof.

To make this bag, a length of tucked paper

tube, like that of Fig. 1, is taken and its lower corners are cut off on lines which are inclined from the longitudinal edges of the tube toward the center thereof. Then the lower end of the tube is opened out and the upper wall thereof is folded back on the transverse dotted line of Fig. 3. That operation causes 35 the formation of the blank of Fig. 4, having the four flaps A, B, C, and D. Then the flaps A and B are folded down on lines coincident with the respective sides of the body of the blank, and after paste has been applied to the 45 presented surfaces of the flaps C and D, as shown in Fig. 5, those flaps are successively folded down on the dotted lines yy and zz , respectively, and the bag of Fig. 7 is thus completed. 50

I claim as my invention—

A paper bag formed from a tube having bellows folds, in which the bottom end of the tube has its outer longitudinal edges severed by cuts which incline from said edges toward the center of the tube, and the opposite free flaps thus formed being folded over toward each other, and the flaps formed from the two faces of the tube lapping over each other and secured by paste or its equivalent, all substantially as described. 55 60

FELIX W. LEINBACH.
